Primary Examiner — Carol P Rademaker(57) **CLAIM**
The ornamental design for a bottle, as shown and described.**DESCRIPTION**

FIG. 1 is a top, front, left side perspective view showing a bottle according to the new design;

FIG. 2 is a front elevational view thereof, the rear elevational view being a mirror image except for the unclaimed thread; FIG. 3 is a right side elevational view thereof, the right side elevational view being a mirror image except for the unclaimed thread;

FIG. 4 is a top plan view thereof; and,

FIG. 5 is a bottom plan view thereof.

The dash-dash-dash-type broken lines shown in the drawing views are included for the purpose of illustrating environmental structure and form no part of the claimed design.

The dot-dash-dot-dash-dot-dash type broken lines shown in the drawing views define the boundaries of the claimed design.
